UNITED STATES PATENT OFFICE.

FRANK M. PIERCE, OF CHICAGO, ILLINOIS.

MUSICAL TOY.

Application filed November 19, 1923. Serial No. 675,493.

To all whom it may concern:

Be it known that I, FRANK M. PIERCE, a citizen of the United States, and a resident of the city of Chicago, in the county of Cook and State of Illinois, have invented certain new and useful Improvements in a Musical Toy; and I do hereby declare that the following is a full, clear, and exact description of the same, reference being had 10 to the accompanying drawings, and to the numerals of reference marked thereon, which form a part of this specification.

This invention relates to a music producing toy and comprises a plurality of metallic members having different timbre with 15 strikers for alternately vibrating said metallic members and a novel form of means for controlling the strikers.

The invention consists in the novel structure and combinations hereinafter described and more particularly pointed out and defined in the appended claims.

In the accompanying drawings which illustrate a preferred form of this invention 25 and in which similar reference numerals refer to similar features in the different views:

On the drawings:

Figure 1 is a top plan view of the toy. 30 Figure 2 is an elevational view of the toy. Figure 3 is a top plan view of the rotary disk showing the metallic members in dotted lines.

Figure 4 is a central vertical section of 35 the toy with parts in elevation.

As shown on the drawings:

In referring to the drawing, it will be observed that the selected embodiment for illustrating this invention comprises a 40 handle 1 having a supporting rod 2 secured therein and extending thereabove. A rotatable drum 3 secured upon the rod just above the handle forms a bearing support for a rotatable disk or member 4 rotatably 45 mounted upon the rod. A sleeve 5 is positioned upon the upper part of the rod 2 and a stationary spider 6 is confined upon the upper end of said rod between the sleeve 5 and a head 7 upon said rod.

50 This spider 6 supports a pair of metallic members 8 which are diametrically located and in the form of pendant bells. In the present embodiment of this invention, these bells are provided with apertures for receiving the ends of the spider arms 6^a which are expanded or split for supporting the bells

as shown in Figure 4. Spaced substantially 90° from the pendant bells 8 are metallic disks 9 which are horizontally arranged and supported by spider arms 6^b in a manner 60 similar to the bells 8. These metallic disks 9 have a different timbre from the metallic bells, and they are located at a higher elevation than the bells 8 for a purpose that will later appear. 65

The disk 4 is adapted to be rotated by a cord or cable 10 which has an upper bifurcated end. The bifurcated ends are of unequal length and they extend through suitable apertures upon opposite sides of the rotating axis of the disks, a small striker 11 in the form of a ball is secured upon the shorter bifurcated end of the cable. The diameter of the ball 11 is such that it will pass under the disks 9 without striking the same. 75 It is however large enough to strike the metallic bells 8 and its supporting bifurcated end of the cable is long enough to allow it to move out by centrifugal force for such a purpose. The section of the cable joining 80 the balls 11 and 12 is in effect a reciprocating member. The diameter of the ball 12 is sufficiently large so that it will strike the disks 9 and the bifurcated end of the cable that is attached to this ball is sufficiently 85 long for such a purpose but not long enough to allow said ball 12 to strike the metallic bells.

The cable is adapted to be wound upon the rotatable drum 3. In operating the toy, 90 the end of the cable thuswise wound is grasped and quickly pulled outwardly thereby rotating the disk 4. A sufficiently powerful pull upon the cable will cause the disk 4 to rotate at such a speed that it will acquire sufficient momentum to continue rotating after the cable is unwound and rewind the cable. When the cable has been thuswise rewound upon the drum 3 the operator may give it another pull and repeat the operation, the disk in such instance, however, revolving in an opposite direction. Thus the disk may be alternately rotated in opposite directions as often as desired. When the disk rotates in one direction, one of the bifurcated ends of the cable will be free so that its ball may travel out by centrifugal force for striking a metallic member; the other bifurcated end will be partially wrapped around the drum 3 so that its ball 110 will be retained close to the pivotal axis of the disk. When the disk rotates in the op-

posite direction, the bifurcated ends of the cable will assume reverse positions, that is the one that was free will be partially wound upon the drum 3 so that its ball or striker will be inoperative, while the other will be free so that its ball or striker may strike the certain metallic members. Consequently different sounds are emitted during opposite rotations of the disk.

10 I am aware that numerous details of construction may be varied through a wide range without departing from the principles of this invention, and I therefore do not purpose limiting the patent granted hereon, 15 otherwise than necessitated by the prior art.

I claim as my invention:

1. In a toy, a rotatable disk, metallic members of different timbre supported above said disk at different distances from 20 the center thereof and at different elevations therefrom, a cable having bifurcated ends of different length extending through said disk upon opposite sides of the rotatable axis thereof, a small striker upon one of the 25 bifurcated ends, a larger striker upon the other bifurcated end and a rotatable drum upon which the cable is adapted to be wound and rewound.

2. In a toy, a rotatable disk, metallic 30 members supported above said disk at different elevations, a cable having bifurcated ends extending through said disk at opposite sides of the pivotal point thereof, different sized strikers upon bifurcated ends of 35 the cable and a drum upon which the cable is adapted to be wound.

3. In a toy, a rotatable disk, metallic members of different timbre supported above said disk, a plurality of strikers 40 mounted on said disk for rotation therewith, and means for rotating said disk and controlling said strikers for causing alternate action thereof upon different metallic members.

4. In a toy, a rotatable disk, metallic members of different timbre supported above said disk at different elevations therefrom, a plurality of strikers of different size, said strikers being slidable on said 50 disk, means for alternately rotating said disk in opposite directions and means associated with said means for sliding said strikers for alternately causing said strikers to strike certain of said metallic members.

5. In a toy, a movable disk, metallic

members supported above said disk, strikers slidably supported on said disk and adapted to be slid into striking position, and means for operating said disk for alternately causing said strikers to strike certain metallic members.

6. In a toy, a rotatable disk, metallic members of different timbre supported above said disk, a pair of strikers and means for rotating said disk and controlling 55 said strikers for causing alternate action thereof upon different metallic members, said means comprising a reciprocating member on said disk connecting said strikers and means connected to said reciprocating member for actuating the same and imparting movement to said rotatable disk.

7. In a toy, a rotatable member, metallic members of different timbre supported above said disk at different elevations therefrom, a pair of strikers of different size and means for alternately rotating said disk in opposite directions and alternately causing said strikers to strike certain of said metallic members, said means comprising a 80 reciprocating member connecting said strikers and means connected to said reciprocating member for actuating the same and imparting movement to said rotatable disk.

8. In a toy, a movable disk, metallic 85 members supported above said disk, strikers, and means for operating said disk for alternately causing said strikers to strike certain metallic members, said means comprising a reciprocating member connecting 90 said strikers and means connected to said reciprocating member for actuating the same and imparting movement to said rotatable disk.

9. In a toy, a movable disk, sound producing members of different timbre supported above said disk, a striker for the member of one timbre, a striker for the member of the other timbre, and means for actuating said disk and alternately causing 95 said strikers to strike their respective members, said means comprising a reciprocating member in substantially the same plane with said disk connecting said strikers and means connected to said reciprocating member for actuating the same and imparting movement to said rotatable disk.

In testimony whereof I have hereunto subscribed my name.

FRANK M. PIERCE.
